UNITED STATES PATENT OFFICE.

WILLIAM WALKER, OF BEDFORD, IOWA, ASSIGNOR OF ONE-HALF TO
ROBERT G. MOON, OF SAME PLACE.

DESIGN FOR A PRESERVING-VAULT.

SPECIFICATION forming part of Design No. 23,167, dated April 3, 1894.

Application filed February 27, 1894. Serial No. 501,725. Term of patent 14 years.

To all whom it may concern:

Be it known that I, WILLIAM WALKER, a citizen of the United States, residing at Bedford, in the county of Taylor and State of Iowa, have invented a new and original Design for Preserving Vaults or Refrigerators, of which the following is a specification.

The invention relates to a new and original design for preserving vaults; and the essential feature resides in a preserving vault having a central cylindrical dome capped body, similar wings, and a triangular front.

In the drawings—Figure 1 is a side perspective of a preserving vault showing my new and original design. Fig. 2 is a front perspective of the same.

Referring to the drawings, 1 designates a central cylindrical body portion provided with a curved top or dome 2; and arranged at opposite sides and the back of the body 1 are

similar shaped wings 3, which are smaller than the body 1.

The preserving vault is provided with a triangular front portion 4, having an upwardly and outwardly inclined bottom 5, and a downwardly and outwardly inclined upper face 6 having an opening 7, and provided at the inner terminus thereof with a vertical extension 8.

What I claim is—

The design for a preserving vault herein shown and described.

In testimony that I claim the foregoing as my own I have hereto affixed my signature in the presence of two witnesses.

WILLIAM WALKER.
